UNITED STATES PATENT OFFICE.

JAMES B. PATTERSON, OF PHILADELPHIA, PENNSYLVANIA.

HEDDLE FOR CROSS-WEAVING.

SPECIFICATION forming part of Letters Patent No. 613,392, dated November 1, 1898.

Application filed August 6, 1897. Serial No. 647,326. (No model.)

To all whom it may concern:

Be it known that I, JAMES B. PATTERSON, of the city and county of Philadelphia, State of Pennsylvania, have invented an Improvement in Heddles for Cross-Weaving, of which the following is a specification.

My invention relates to heddles for cross-weaving; and it consists of the improvements which are fully set forth in the following specification and are shown in the accompanying drawings.

More particularly my invention relates to heddles designed for cross-weaving, and especially to the heddles or devices for effecting the crossing of the warp-threads.

My invention relates to improvements in doup-heddles which control doup threads or warps and operate to cross them over other threads or warps in the formation of the sheds in weaving. These doup-heddles consist of a series of strips or members combined with doup-needles which control the doup threads or warps and operate to lift them first on one side of the free warp and then on the other without the necessity of shifting the heddles laterally. In devices of this kind difficulty has been experienced heretofore in effecting the crossing of the threads with certainty and precision, and this has been particularly the case in fine weaving, where the threads must be brought very close together.

The objects of my invention are to enable the crossing of the threads to be effected with facility and precision, to prevent the doup-needles from catching on or passing on the wrong side of threads, to enable the doup-heddles to perform fine work, to enable the heddle members to be easily and quickly put together and the doup-needles to be applied and removed, to enable the doup-needles to move freely and without liability of binding or twisting, to maintain the heddle strips and needles which compose the heddle in proper position, and to simplify the construction.

My improvements relate particularly to the construction of the heddle-strips and doup-needles and to the combination thereof in the formation of the heddle.

I shall now refer to the accompanying drawings for the purpose of more particularly describing my improvements.

Figure 1 is a front elevation of a heddle strip

or member embodying my invention. Fig. 2 is a longitudinal vertical sectional view of the same on the line *xx* of Fig. 1. Fig. 3 is a transverse sectional view on the line *yy* of Fig. 1. Fig. 4 is a perspective view of the detached doup-needle. Fig. 5 is a front view of a portion of a heddle made up of my improved heddle strips or members; and Figs. 6, 7, and 8 are diagrams illustrating the operation of the heddle-strips in crossing the warps.

A is the heddle-strip, consisting, preferably, of a flat strip of metal bent forward at about the middle to form a small shoulder or offset *a*, having the side edges *bb* of the lower portion bent inward to form a longitudinal guide-way for the doup-needle, with a flat base *c*, and also having a longitudinal guiding-eye *d* stamped or formed immediately below the offset or shoulder *a* and the two sides of the strips bent up to form guiding-wings *ee*, adjacent to the shoulder *a*. The strip *A* is also formed with openings *oo* above and below the guide *d* to facilitate the application and removal of the needle and to form a guide therefor.

B is the doup-needle, which preferably has a body *f* of round cross-section and is provided at the top with an eye *g* and at some point in its length, preferably at the base, with a flattened guide *h*, adapted to the guide-way formed by the flat base *c* and bent edges *bb* of the strip *A*.

The eye *g* is preferably formed by flattening the end of the needle *B* transversely to the flattened guide *h* on the body of the needle and has its head tapered, as at *ii*, so as to prevent the free thread from catching thereon and to assist in properly guiding the thread over the needle. The eye-opening is preferably elongated and extends to as great extent as possible to the top of the eye, so as to bring the doup-needle thread as close as possible to the free thread during the operations.

The needle *B* is applied to the strip *A*, so that the body *f* extends through the guide *d*, with the eye *g* just above it and below the wings *ee*. The needle may move freely on the strip *A*, (its downward movement being limited by a stop,) and the flattened guide *h* travels in the guide in the base of the strip

A. As the guide *h* is flattened and travels in a correspondingly-flattened guideway in the strip A, the needle B will be held against turning, so that the eye *g*, which is arranged transversely to the guide *h*, will be maintained in proper position. By making the body of the needle B round and using the small flattened guide *h* friction is reduced to a minimum, and there is consequently little liability of the needle to bind in the guide of the strip A and not to move freely thereon, as is necessary to the successful operation of the heddle.

The harness is composed of a series of the strips A, arranged adjacent to one another, as illustrated in Fig. 4. To enable the strips to be easily placed together and to be properly spaced, as well as to prevent the twisting or turning of any of the strips, which would be liable to interfere with the crossing of the threads, I prefer to bend over the ends of the strips, as at *j*, to form a loop having two parallel sides *k k*, which are provided with openings *l l* to receive the heddle wire or strip C. The strips A A are placed side by side on the heddle wire or strip C, with the bent-over loops butted together, which thus act to keep the strips properly spaced apart. As the heddle-bar C passes through the openings *l l* in the two pieces *k k* of the loop the heddle-strips will be firmly supported and prevented from twisting or turning.

At the base I prefer to bend the strip, as at *m*, to form a shoulder which acts as a stop to limit the downward movement of the doup-needle B and to maintain its eye *g* in proper position. The lower end of the strip is provided with an opening *n* to receive the heddle-bar D.

I prefer to leave the side edges *b b*, which form the sides of the needle-guideway on the strip A, open at the base adjacent to the stop or shoulder *m*. This prevents the end of the guideway from becoming closed or clogged up, which might interfere with the free movements of the doup-needle, and also facilitates the application of the needle to the strip and its removal therefrom. To remove the needle, the lower end, which is provided with the guide-wing *h*, is drawn down and sprung outward free from the stop or shoulder *m*, when the needle may be readily drawn out, the openings *o o*, adjacent to the guiding-eye *d*, permitting the needle-eye *g* to be disengaged. To apply the needle, the operation is reversed. The needle is pushed upward in the guideway *c* until the eye *g* is immediately below the needle-guideway *d*, when the eye is passed behind the guide *d* through the openings *o o*, and the guide-wing *h* is simultaneously sprung over the shoulder *m* into engagement with the guideway *b b c*.

In Figs. 6, 7, and 8 I have illustrated the operation of the heddle in crossing the threads. *s* is the free thread or warp, and *t* is the doup-needle thread or warp, which passes through the eye *g* of the doup-needle B. It is under-

stood that the free warp of one heddle may be the doup-needle warp of another heddle, and vice versa.

When the heddle and doup-needle are at rest, as in Fig. 6, the free warp *s* lies above the eye *b* of the doup-needle. When the doup-needle thread is lifted, which is accomplished by suitable heddles or lifting-wires, (not shown,) the needle B is lifted also and passes above and outside of the free warp *s*, as shown in Fig. 7. This is effected because the free warp lies above the wings *e e* inside of the line of movement of the doup-needle. When the warp *t* is released, the doup-needle falls back into its former position, carrying the warp *t* with it. When the heddle-strip A is lifted, the doup-needle and warp *t* are lifted also and pass above the free warp *s*, which is, however, pushed outward by the wings *e e*, so that it lies on the outside of the needle B, crossed over the doup-needle thread, as shown in Fig. 8.

I do not limit myself to the details of construction which have been shown for the purpose of illustration, as they may be varied without departing from the invention.

Having now described my invention, what I claim as new, and desire to secure by Letters Patent, is as follows:

1. A heddle strip or member bent in its length to form an offset and provided with a thread-guiding projection and a needle-guide adjacent to said offset, and having the side edges of its lower portion bent as at *b b* to form a guideway with a flat base *c*, in combination with a doup-needle provided with a flat guide-wing *h* adapted to the guideway of the strip and moving on the flat base *c* thereof. 105

2. A heddle strip or member bent in its length to form an offset and provided with a thread-guiding projection and a needle-guide adjacent to said offset, and having the side edges of its lower portion bent as at *b b* to form a guideway with a flat base *c*, in combination with a doup-needle, provided with a flat guide-wing *h*, adapted to the guideway of the strip, and moving on the flat base *c* thereof, and having, at its upper end, a flattened eye *g*, arranged transversely to the flat guide-wing *h*. 115

3. A heddle strip or member bent in its length to form an offset and provided with a thread-guiding projection and a needle-guide adjacent to said offset, and having the side edges of its lower portion bent as at *b b* to form a guideway with a flat base *c*, in combination with a doup-needle, provided with a flat guide-wing *h*, adapted to the guideway of the strip, and moving on the flat base *c* thereof, and having, at its upper end, a flattened eye *g*, with the side edges of its heads tapered as at *i i*, arranged transversely to the flat guide-wing *h*. 120

4. A heddle strip or member having the side edges of its lower portion bent as at *b b*, to form a longitudinal guide with a flat base *c*, in combination with a doup-needle provided

with a flat guide-wing, adapted to the guide of the strip and moving on the flat base *c* thereof.

5. The heddle-strip, consisting of a flat piece of metal bent in its length to form an offset *a*, and provided with a needle-guide adjacent thereto, and having one end bent as at *j* to form a loop, having two sides *k* *k* provided with openings *l*, *l*, and its other end bent as

at *m* to form a shoulder, and provided near *io* its extremity with an opening *n*, substantially as and for the purpose described.

In testimony of which invention I hereunto set my hand.

JAMES B. PATTERSON.
